UNITED STATES PATENT OFFICE.

ADDIE H. HORNSBY, OF OMAHA, NEBRASKA.

DOLL.

1,417,915.

Specification of Letters Patent. Patented May 30, 1922.

Application filed July 29, 1920. Serial No. 399,680.

To all whom it may concern:

Be it known that I, ADDIE H. HORNSBY, a citizen of the United States, residing at Omaha, in the county of Douglas and State 5 of Nebraska, have invented certain new and useful improvements in Dolls; and I do hereby declare the following to be a full, clear, and exact description of the invention, such as will enable others skilled in the art 10 to which it appertains to make and use the same.

This invention relates to dolls, and more particularly to a doll made of paper or fabric.

15 One of the main objects of the invention is to provide a doll which may be readily formed by folding from a single piece of material. A further object is to provide a doll and garments therefor which may be 20 cut in the form of a blank from a single piece of material, this blank being then folded so as to position the garments properly about the doll. Further objects will appear from the detailed description.

25 In the drawings:

Figure 1 is a front plan view of the blank from which the doll is formed.

Figure 2 is a front view of the doll formed by folding the blank.

30 Figure 3 is a back view of the same.

In constructing the doll, I cut a suitable blank, such as that illustrated in Figure 1, from a sheet of paper or fabric, this blank being so shaped that by properly folding the 35 same the doll and the garments therefor may be readily positioned in proper relation and secured together. The blank is cut to provide a relatively broad arcuate member 1 provided at one end of its inner edge with a 40 reduced tab 2, and at the other end of its inner edge with a reduced extension 3 having at the inner edge of its outer end a relatively narrow tab 4 which carries a plurality of streamers 5. The reduced extension 3 is 45 further provided, at the central portion of the inner edge thereof, with an inwardly extending and inwardly flaring member 6 the central portion of which is cut out in substantial V-shape to provide a tie 7 which 50 is formed by bending the material outlined by said cutout downwardly, in a manner to be described, the opening thus provided constituting a substantially V-shaped yoke opening, as in Figure 2. The inner edge of 55 member 1 is connected, a short distance from the end thereof carrying the extension 3, by

an element 8 to the shoulders of body 9 of the doll, the central portion of element 8 being cut out to provide the head 10 for the body. Element 8 is provided at each side 60 with a lateral substantial segmental extension 11 having an inwardly extending tab 12 at the outer corner of its inner edge, each of these extensions being provided at the outer corner of its outer edge with a tab 13. 65

To form the doll with the garments thereon, the element 8 is turned downwardly in front of the upper portion of body 9 along a line 14 extending across the shoulders of the body 9. This positions the main member 1 in front of and at the lower portion of the body. After this has been done, the portion of member 1 at the side of the body opposite to that at which the extension 3 is 70 positioned, is folded rearwardly and inwardly upon itself a number of times, along the lines 15, 16 and 17, the line 17 extending along the right hand side of the body as considered in Figure 1, and the tab 2 is 75 folded inwardly along the line 18 and passed 80 about the body at the waist portion thereof, thus securing the folded portion of the member 1 to the body. The other end portion of member 1 is then folded backwardly behind the body along the line 19, the extension 3 85 being then folded along line 20 so as to extend across the front of the body and then folded backwardly along line 21 so as to extend across the back of the body, after which each of the extensions 11 are folded 90 along the line 22 so as to extend about the back of the body over the arms of the figure in overlapping relation, the tab 4 being then passed inwardly over tab 13 of the inner extension 11 so as to secure the same in position, and the streamers 5 being positioned 95 so as to be in superposed relation as in Figure 3. After this has been done, head 10 of the figure is inserted through the opening 100 23 of the member 6, this member being 100 folded downwardly and rearwardly of the figure along the line 24 at the neck of the figure to provide a collar of the sailor type, the tie member 7 being folded downwardly 105 and outwardly so as to present the appearance of a tie at the lower end of the yoke opening of this collar. The tab 12 of the outer extension 11 is then turned outwardly and downwardly at right angles over the collar so as to secure this member in position, the tab 12 of the other extension having 110 been turned downwardly and inwardly so as

to provide a reinforcing element for the neck of the figure. In this manner, the doll may be readily formed from a single piece of material by properly folding the same, 5 the garments being properly positioned upon the figure of the doll and secured together.

While the doll illustrated is shown as formed from smooth paper folded, it will 10 be understood that I may employ any other suitable material for this purpose, and that the material may be plaited or plane as desired. Also, if so desired, in cutting the 15 blank or pattern the doll may be provided with a hat and a parasol, and other articles of a similar nature designed to impart a more pleasing appearance to the figure produced.

What I claim is:

20 1. A toy made from blank material having a body portion and an incision adjacent to the same to define a head portion, and a garment portion foldable intermediate the body portion and head portion substantially 25 along the line of the shoulders and over the body portion.

2. A toy made from blank material having a body portion and an incision adjacent to the same to define a head portion, a garment portion foldable intermediate the body portion and head portion substantially along the line of the shoulders and over the body portion, said garment portion having an 30

opening through which the head portion is insertible.

3. A toy made from blank material having a body portion and an incision adjacent to the same to define a head portion, a garment portion foldable intermediate the body portion and head portion substantially along 40 the line of the shoulders and over the body portion, said garment portion being extended laterally for wrapping about the body portion, and cooperating means on the blank to maintain the garment portion 45 wrapped about the body portion.

4. A toy made from a blank having an incision to define a head portion, the blank having a body portion, arm portions extending from the body portion below the head portion, the blank having a garment portion foldable intermediate the head portion and body portion substantially along the line of the shoulders toward and to cover the body portion and said arm portions, said garment 50 being provided with an incision through which the head portion may be inserted, and coacting fastening means, the extremities of the garment portion.

In testimony whereof I affix my signature 60 in presence of two witnesses.

ADDIE H. HORNSBY.
